UNITED STATES PATENT OFFICE.

ALBERT H. COBLE, OF FRANKFORT, INDIANA.

COLOR GAME.

Application filed June 10, 1921. Serial No. 476,396.

To all whom it may concern:

Be it known that I, ALBERT H. COBLE, a citizen of the United States, and a resident of Frankfort, county of Clinton, and State 5 of Indiana, have invented a certain new and useful Color Game; and I do hereby declare that the following is a full, clear, and exact description thereof, reference being had to the accompanying drawings, in 10 which like numerals refer to like parts.

This invention relates to a game and the chief object thereof is to provide playing elements which are suitably colored for color matching purposes.

15 The chief object of the invention is to utilize colors upon suitable playing elements so that said elements may be employed in a game wherein the elements are matched according to color so that the game will be interesting as well as instructive.

20 The chief feature of the invention consists in providing a color game with a plurality of playing elements each having a portion of its surface suitably colored, 25 whereby said playing elements may be employed in a game.

The full nature of this invention will be understood from the accompanying drawings and the following description and 30 claims.

In the drawings Fig. 1 is a plan view of a box and the playing elements therein. Fig. 2 is a plan view of the inside of the cover of the box shown in Fig. 1. Fig. 3 shows 35 one of the games played with the elements and shows said elements in the process of playing.

In the drawings 10 indicates a rectangular box which is substantially square and 40 contained therein are thirty six blocks designated generally by the numeral 11. The box 10 is provided with a cover 12 and the inside of said cover depicts the following: In the left hand portion of the cover 45 there is shown a plurality of parallel rays passing through two prisms which have their apices adjacent each other, each showing the dispersion of the light rays of all the rays passing through the prism except 50 that ray which passes through the apices of the prism, which is a white ray. In the right hand portion of the cover there is shown a pair of similar prisms placed base to base and the plurality of parallel light 55 rays which are passed through these prisms are directed inwardly together and form

black. In the central portion of the cover there is shown a plurality of parallel rays striking a prism while after passing through the same are dispersed into the respective 60 colors that include, as shown, the primary and secondary colors, to wit, violet, blue, green, yellow, orange and red in the order named. Positioned beneath all of the aforesaid is a rectangular portion divided into 65 eight divisions, each division being suitably colored as indicated and each having a numerical value arbitrarily assigned thereto. Thus, white, which is the left hand division, and black, which is the right hand 70 division, are arbitrarily assigned values one and eight respectively. Yellow, violet, orange, green, red and blue are assigned the values 2 to 7 inclusive respectively for playing purposes. These values are purely arbitrary and may be varied as desired.

While the invention broadly includes a plurality of playing elements, these elements, while they may be in the form of cards, are preferably in the form of blocks and it has 80 been found that rectangular blocks which are substantially in length twice the width thereof lend themselves more readily to playing purposes. The blocks therefor include any playing element of any convenient 85 form or material. The blocks, and in the present instance, the rectangular blocks, are preferably divided across the middle forming equal areas at each end, and these areas are suitably colored. Thus, one group of 90 blocks contains areas colored with the primary colors. Another group of blocks contains areas which are colored with the secondary colors. While a third group of blocks contains areas which are colored with 95 secondary and primary colors. Two additional groups of blocks are also provided and one of these groups includes blocks having one playing area provided with white colors and the other playing area provided 100 with another color, either primary or secondary or black. Similarly the other group of blocks or playing elements has one portion of its area colored black and the other portion provided with one of the colors, 105 either primary or secondary.

Another block is provided which takes the place of the double black block although the same may be provided if desired. This block is arbitrarily assigned the numerical 110 value 15. This block, as shown in both Figs. 1 and 3, and in Fig. 3 is the central block.

Therein said block is designated by the numeral 13 in Fig. 3 and is termed the joker block. One end thereof is suitably colored with the primary colors, while the opposite end thereof is suitably colored with the secondary colors. The intermediate portions of the block are colored with both white and black pigment for a purpose herein-after to be described. Thus, the game includes six primary colored blocks, six secondary colored blocks, nine compound color blocks, fourteen blocks each having white or black on one portion thereof, and the joker block, making a total of 36. The game may be extended beyond the aforesaid elements since it is to be noted that while red and yellow, primary colors, combined make orange, and red and blue, primary colors, combined make violet or lavender, orange and violet in turn when combined together make russet or a tertiary color. The tertiary colors are citron, olive and russet. These colors also may be included in the game and combinations thereof in turn may be included in the game, thus extending the game to a larger number than 36 blocks.

From the foregoing it will be noted, therefore, that this game is instructive and educational since it teaches the difference between the several colors and also whether said colors are primary or secondary colors or whether they contain any color or all the colors. Various kindergarten and primary accessories may be worked out with the use of these colored blocks and by their use color blindness can be readily determined in the child as well as the adult. Also many unique designs and figures may be made with the color blocks arranged in the box containing the same. These blocks also teach color blending.

Herein there is given the rules for three games which are typical of those which may be played with the colored elements. The colored blocks or elements are all turned color side down and back up upon a suitable support, such as a table or stand and are shuffled until well mixed. Two or more players may play the game and it has been determined that each player should draw from the color camp which includes all of the color blocks upon the table, not less than five color blocks, and in a two handed game it has been determined that ten color blocks provide the greatest interest. The game is played by matching colors and when completed the values of the colors is ascertained by the arbitrary scale heretofore mentioned and described.

In the first game each player turns up a color block and the one having the highest value color block plays first and the play continues from right to left. The next player plays a block end to end against the first block with the adjacent ends having

colors matched. Thus, a red end block is played on the red end of the first block, if said block has a red end. Blocks having the same color on both ends are called doubles and are played crosswise and after playing on both sides of the doubles the ends may also be played upon. Preferably playing upon the ends of the double is restricted to the first double played in the game. Each time that a player fails to play a color block on the playing color lines, said player is penalized by being compelled to take a color block from the color camp. The first player who is able to match his blocks in his turn with those on the board wins the round or game and the blocks retained by the other players are then valued according to any arbitrary scale, such as that shown in Fig. 2, and said players are penalized to the extent of their score. This game may be extended by repeating the play heretofore described and keeping a record of each player's score, the player having the lowest score for any predetermined number of completed plays as heretofore described, wins the game. If the play becomes blocked the player who holds the lowest valued color cards or colored blocks wins the game.

Another game which can be played with the color blocks includes the joker and the player having the joker plays first, and if no player has the joker then each player turns up a color block to see who plays first. The player turning up the joker plays first and the one so doing returns one of his color blocks to the color camp and shuffles the same therein. If the joker should not be turned up then the player turning up the color block having the highest value plays first. The first double played is the leader double and may be played on both sides and thereafter on the ends. When the joker is drawn from the color camp it must be played as a double if there is a white or black playing area exposed at either end of the playing line. If not then it may be played lengthwise at an end where there is a primary or secondary color having the primary end abutting the primary color or the secondary color matching the secondary color. Therefore, when the joker is played the joker in this manner is the same as one of the compound color blocks. The playing is continued as in the regular game and the count may be made either by games or by values.

The more scientific game, which also teaches color variations, may be termed the scientific game, of which there may be two variations. The joker is played in this game (see Fig. 3) and after the color blocks have been shuffled, back up and colors face down, the player turning up the highest valued color block plays the joker. The next player is arbitrarily limited to play upon the side

of the joker and the color block that is played must have either white or black at one end. If white is played on one side of the joker then black must be played on the other side of the joker. The ends of the joker can not be played upon until both sides of the joker have been played upon and no blocks may be played on the blocks played at the sides of the joker excepting those blocks which have either white or black on one portion thereof. After both sides of the joker have been played upon, the ends of the joker may be played as well as the sides thereof. The primary color blocks are played only on the ends of the joker having the primary colors, the secondary color block being played only on the end of the joker having the secondary color blocks. Compound color blocks may be played on either end so long as they match, but cannot be played on either of the black and white lines. No primary colors can be played on the secondary lines in one variation of this game. Thus, if the compound orange and blue is played on the secondary side of the joker, or the secondary line, a block colored with blue and yellow cannot be played by matching blue to blue since the blue and yellow block is a primary block. Similarly secondary blocks cannot be played on the primary line, even though the secondary color be exposed on the primary line. Thus, in the restricted scientific variation it is always necessary that two compounds be played in succession in order to return in the primary line from the secondary to the primary colors and in the secondary line from the primary colors to the secondary colors. The first player who is able to play from his color camp all of his color blocks wins the hand and is credited with the values assigned to the color blocks held by his opponent. If desired, the value of the game may be otherwise determined by giving to the winning player the values of the color blocks held by the other players and assigning a definite value such as 100 or 1000 or some other value as the score to be reached by the winning player. It is thus desirable if possible throughout all the games to first dispose of the colored blocks having the highest values so that not only must the matching of colors be considered in the playing of the game but also the value of the colors as assigned to the same.

Various modifications may be made in the playing without departing from the broader features of the invention, reference being had to the appended claims.

60 The invention claimed is:

1. A game including a plurality of playing elements, each having its surface divided into portions and said portions suitably colored for color matching purposes, one

group of elements being colored with primary colors, another group of elements being colored with secondary colors, a third group of elements each having a primary and secondary color thereon, and another group of elements each having a white portion and a colored portion. 65 70

2. A game including a plurality of playing elements, each having its surface divided into portions and said portions suitably colored for color matching purposes, one group of elements being colored with primary colors, another group of elements being colored with secondary colors, a third group of elements each having a primary and secondary color thereon, and another group of elements each having a black portion and a colored portion. 75 80

3. A game including a plurality of playing elements, each having its surface divided into portions and said portions suitably colored for color matching purposes, one group of elements being colored with primary colors, another group of elements being colored with secondary colors, a third group of elements each having a primary and secondary color thereon, another group of elements each having a white portion and a colored portion, and another group of elements each having a black portion and a colored portion. 85 90

4. A game having a plurality of playing elements, each having its surface divided into portions and said portions suitably colored for color matching purposes, one group of elements being colored with primary colors, another group of elements being colored with secondary colors, a third group of elements each having a primary and secondary color thereon, a joker element having all the primary colors upon one portion and all the secondary colors upon another portion. 95 100

5. A game including a plurality of playing elements, each having its surface divided into portions and said portions suitably colored for color matching purposes, one group of elements being colored with primary colors, another group of elements being colored with secondary colors, a third group of elements each having a primary and secondary color thereon, another group of elements each having a white portion and a colored portion, another group of elements each having a black portion and a colored portion, and a joker element substantially 110 115 120 as set forth.

6. A joker element for a color game having a portion of its surface suitably divided and each division differently colored within itself substantially as set forth. 125

In witness whereof, I have hereunto affixed my signature.

ALBERT H. COBLE.
